UNITED STATES PATENT OFFICE.

HARRY P. SHOTTS, OF CHICAGO, ILLINOIS, ASSIGNOR TO HOWE AND DAVIDSON COMPANY, OF EAST ORANGE, NEW JERSEY, A CORPORATION OF NEW JERSEY.

PAPER TRAY OR RECEPTACLE.

No. 823,898.

Specification of Letters Patent.

Patented June 19, 1906.

Application filed June 6, 1903. Serial No. 160,301.

To all whom it may concern:

Be it known that I, HARRY P. SHOTTS, of Chicago, in the county of Cook and State of Illinois, have invented certain new and useful Improvements in Paper Trays or Receptacles; and I do hereby declare that the following is a full, clear, and exact description thereof, reference being had to the accompanying drawings, and to the letters of reference marked thereon, which form a part of this specification.

This invention relates to improvements in trays and other like receptacles or articles made of paper or other flexible sheet material and provided with a flat end wall and a continuous wall or rim surrounding said end wall and to an improved blank for making such article.

The device herein illustrated is especially applicable for use as a tray for packing in pails candies and like merchandise, and when used in this manner the trays are filled and placed in a candy-pail one over the other, said trays thus serving as horizontal separators or partitions by which the layers of candy in the pail are separately supported. A device having the same features of construction may, however, be used for other purposes, as will hereinafter more fully appear.

As shown in the drawings, Figure 1 is a plan view of a blank made in accordance with my invention for making the tray hereinafter to be described. Fig. 2 illustrates the manner of cutting two like blanks from a strip of sheet material. Fig. 3 is a perspective view of a finished tray made in accordance with my invention. Fig. 4 is a plan section taken on line 4 4 of Fig. 5. Fig. 5 is a cross-section 40 taken on line 5 5 of Fig. 4. Fig. 6 is a bottom perspective view thereof.

As shown in said drawings, A, Fig. 1, indicates a blank in flat form from which my improved tray is made. Said blank consists of an elongated marginal strip A', extending from end to end of the blank and provided on one side thereof with a plurality of integral outwardly-tapered contiguous projections A². Each of said projections A² has converging side margins which converge toward the outer end of the projection and constitute two sides of a triangle. The other sides or bases of the triangles are defined by score-

lines a, which extend lengthwise of the blank along the bases of said triangles. Said score-lines are, in the preferred form of the blank, curved to correspond with the curvature of the annular wall or rim of the tray which is to be formed from the blank. One end of the marginal part A' of the blank is provided with a longitudinal locking-slit a', and the other end of said marginal part of the blank is provided with a short transverse locking-tongue a², which when the ends of said marginal part of the blank are brought together 55 enters said locking-slit and locks said blank in a circular form. The locking tongue and slit are so located with respect to the end projections A² of the blank that when the blank is bent to circular form in the manner stated the 60 end projections, which are at this time brought together, occupy the same relation to each other as do adjacent projections between the ends of the blanks. Said projections A² are adapted to be bent inwardly 65 along the score-line a at right angles to the marginal part A' of the blank, so that they will together constitute the end or bottom wall of the tray or like device which is formed from said blank. When said projections are 70 thus bent or folded inwardly and the marginal part of the blank is bent to form a circle, the points of the projections A² are brought together at the center of the tray thus formed, and said projections A² constitute radial converging sectional parts of the 75 bottom or end wall of the tray or the like. The marginal part A' constitutes when the tray is thus formed the vertical circular wall or rim of said tray. The sectional parts of 80 the end or bottom wall of the tray are fastened together to constitute a rigid unitary wall by means of a disk B of sheet material, 85 which is pasted or otherwise secured to either the inner or outer side of the end or bottom 90 wall of the tray, said disk being herein shown as secured to the outer side of said wall. The disk B is herein shown as made much smaller 95 in diameter than the tray, but may be made as large in diameter as necessary to provide 100 the required strength in the end or bottom wall of the tray.

As shown in the drawings, the rim A' of the tray is made to assume a circular form and this form of the rim being possible because of the curved form of the score-lines a

at the bases of the triangular projections, which score-lines are curved concentrically with the apices of the said projections.

The tray is provided with a plurality of 5 radial vertical partition-strips C C' C², preferably three in number. Said partition-strips are made integral or in one piece with the blank A, as shown in Fig. 1, the same being originally parallel with the main marginal strip A' of the blank and separated therefrom in the case of the strip C by a slit c and in the case of the strips C' and C², which are continuous with each other, by a slit c'. The said partition-strips are permanently 10 joined to the main strips A' by means of connecting parts c² c³ c⁴, which are continuous with the strips C, C', and C², which form lateral extensions of the said main strip A' and which are adapted to be folded inwardly 15 against said main strip A'. Score-lines c⁵, c⁶, and c⁷ are preferably formed along the line dividing the connecting parts c², c³, and c⁴ with the main strip to facilitate the folding of the connecting-strips in the manner stated. 20 Said score-lines c⁵, c⁶, and c⁷, together with the slots c and c', serve to outline the principal part of the outer edge of the strip A'.

In folding the blank when provided with parts for forming radial partition-strips, as 25 described, the connecting-pieces c², c³, and c⁴ are folded inwardly against the strip A' when the blank is still flat. The blank is then bent into circular form and the ends of the blank joined, the connecting parts c², c³, 30 and c⁴ then lying inside of the wall or rim of the tray, as seen in Figs. 3 and 4. The partition-strips C, C', and C² are then bent inwardly to form the radial partitions, the connected strips C' and C² being bent at their 35 meeting ends at an angle to each other, as seen in Fig. 4. The meeting ends of said strips are then fastened together. A simple means for connecting said ends is shown, consisting of a notch c⁸, formed at the joining 40 point of the connected strips C' and C² and a notch c⁹ in the strip C near its end, said notches extending laterally into the strips from opposite sides thereof, so that they 45 may be readily interlocked with each other, as seen in Fig. 3.

In Fig. 2 I have shown a method of cutting from an oblong rectangular blank of sheet material two of the blanks shown in Fig. 1. By reference to said figure, which shows in 55 dotted lines the outline of two like blanks, it will be observed that two blanks may be cut from an oblong rectangular blank of a length but slightly greater than the length of one of the blanks and with the result of wasting but 60 little of the material, the wasted material being located at the ends of the blank and being indicated by a⁴ in Fig. 2. In cutting the blank from an oblong rectangular sheet, as herein shown, a cutting-die may be provided 65 having cutting edges corresponding in shape

to the zigzag line a⁵, which divides one blank from the other and forms the triangular projections of the finished blank, and providing said die also with cutting edges corresponding with the dotted lines a⁶, by which is 70 formed the tongues of the blank. Said cutting-die may also be provided with cutting edges corresponding in shape and location with the end margins of the blank and the slits a', c, and c' thereof. In this manner it 75 will be seen that two blanks may be cut from a single sheet of paper at one operation of a suitable cutting-tool, and thus the making of such blanks greatly facilitated and with the loss of but little of the material from which 80 they are made.

Manifestly the tapered projections described need not be pointed, because when the disk B is used to hold them together the ends of the projections may be cut off or 85 shortened, the disk covering the space left at the middle of the tray by so doing. This construction is not usually desirable, however, because in cutting two blanks from a single sheet, as shown in Fig. 2, there will be 90 no saving of material effected by shortening the projections. In cutting each blank from a single narrow sheet, however, a saving of material would be effected by so shortening the projections. 95

I claim as my invention—

1. A tray comprising a rim made from a single strip which is joined at its ends and is provided on its lower edge with lateral, tapered projections which form the bottom of the tray, and a plurality of radial partitions each consisting of a strip, the base of which is joined laterally to the upper edge of the rim and is folded inwardly on said rim. 100

2. A blank for making trays or the like consisting of a single main strip having lateral projections adapted to form the bottom of the tray and three partition-strips parallel with the main strip and joined to the same by connecting parts which project laterally from 105 the main strip, two of said partition-strips being connected at their ends or made continuous with each other. 110

3. A blank for making trays or the like consisting of a single main strip having lateral 115 projections adapted to form the bottom of the tray and three partition-strips parallel with the main strip and joined to the same by connecting parts which project laterally from the main strip, two of said partition-strips being connected at their ends or made continuous with each other, the two connected strips being provided with a locking-notch at their meeting ends and the third strip having a locking-notch near its extremity. 120

4. A tray consisting of a rim made from a continuous strip; a bottom consisting of lateral, tapered projections on the main strip, and radial partition-strips joined to the main strip by connecting parts which are made in- 125 130

tegral with the main strip and are folded inwardly against the same.

5. A tray consisting of a rim, a bottom wall, and radial partition-strips joined at their outer ends to the rim by connecting parts which are integral with the rim and are folded inwardly against said rim, said partition-strips being joined at their inner ends to each other.

10. 6. A tray consisting of a rim, a bottom wall, and a plurality of radial partition-strips joined at their outer ends to the rim by connecting parts which are integral with the rim and are folded inwardly against the same, said strips being provided with lateral notches whereby they may be interlocked at their inner ends.

7. A tray consisting of a rim, a bottom wall, and three radial partition-strips, two of which are made continuous with each other, and which are joined at their outer ends to the said rim by connecting parts which are integral with said rim and folded inwardly against the same; the two connected strips

being bent at an angle to each other at their 25 meeting ends, and the free end of the third strip being attached to the meeting ends of the said connected strips.

8. A tray consisting of a rim, a bottom wall, and three radial partition-strips, two of 30 which are made continuous with each other and which are joined at their outer ends to said rim by connecting parts which are integral with said rim and folded inwardly against the same; the two connected strips being 35 bent at an angle to each other and provided with a notch at their meeting ends and the third strip having a notch adapted to interlock with the notch at the meeting ends of the connected strips.

In testimony that I claim the foregoing as my invention I affix my signature, in presence of two witnesses, this 22d day of May, A. D. 1903.

HARRY P. SHOTTS.
